Primary Examiner — Catheri Oliver-Garcia*Assistant Examiner* — Rebekah Caruso(74) *Attorney, Agent, or Firm* — Buche & Associates, P.C.; John K. Buche; Scott D. Compton(57) **CLAIM**

The ornamental design for a pedicure spa, as shown and described.

DESCRIPTION

FIG. 1 is a front perspective view of a pedicure spa showing my new design;

FIG. 2 is a left side elevational view thereof;

FIG. 3 is right side elevational view thereof;

FIG. 4 is front elevational view thereof;

FIG. 5 is a back elevational view thereof; and,

FIG. 6 is a front perspective view of the pedicure spa in its environment.

The ornamental design which is claimed is shown in solid lines in the drawings. The broken lines in the drawings depict environmental structure and form no part of the claimed design.
